ABSTRACT OF THE DISCLOSURE

Check straps of conical formation made from nylon or the like fabric, characterized by shrinking an elongated edge area of the strap, thus imparting an edgewise curvature thereto and then joining the ends of the strap.

This invention comprises a new and improved check strap of the type that is employed in loop formation with one side of its loop held at a fixed point in the loom while the other side is engaged in sliding contact by friction fingers.

I have found that the life of a woven strap of this type may be improved by imparting to it a preformed initially conical formation corresponding substantially with the angle of the picker stick at the end of its stroke. This ensures full transverse contact of the picker stick across the entire width of the strap and an even distribution of impact stress in the strap. It contributes therefore to reduce wear and to adapt the strap for use in high speed looms.

The desired conical formation may be imparted to a strap of woven nylon fabric by shrinking one edge of a straight strap in a marginal zone. As herein shown the shrinking step is effected by the application of heat and pressure to a selected predetermined area of the strap, but it would be within the scope of the invention to employ chemical shrinkage treatment. The shrinking step may be followed or preceded by a step of impregnating the strap in spaced areas in order to reinforce it against reeling by and impact of the picker stick.

As herein shown one impregnated area of the strap lies beyond the grip of the friction fingers and extends forwardly into the bend of the loop. It thus includes that portion of the strap which must reeve about the picker stick in its driving stroke and which must come entirely from that side of the loop which is arranged to move through the friction fingers, since the strap is fixed in the other side of the loop.

These and other features of the invention will be best understood and appreciated from the following description of a preferred embodiment thereof, selected for purposes of illustration and shown in the accompanying drawings, in which:

FIG. 1 is a plan view of the check strap in its shape and location at the beginning of the driving stroke of the picker stick,

FIG. 2 is a similar view of the check strap as it appears at the end of the picker stick stroke,

FIG. 3 is a fragmentary view in elevation corresponding to FIG. 2,

2

FIG. 4 is a plan view of a straight strap on a somewhat smaller scale,

FIGS. 5 and 7 are diagrammatic views suggesting the shrinking step, and

FIGS. 6 and 8 are plan views of the strap as impregnated and as curved by the shrinking step.

The strap 10 is close woven of nylon yarn or other tough thermoplastic synthetic resin and may be about two inches in width and $\frac{3}{16}$ in thickness. For present purposes 10 the strap as shown in FIG. 4 may be considered to be about 23 inches in length and when doubled as shown in FIG. 1 form a loop with an overall length of about nine and one-half inches. The strap has slots or perforations 11 at both ends for the reception of a clamping bolt 16 which confines the strap to its loop formation and secures it to a fixed bracket 17.

As best shown in FIG. 6 the strap is impregnated with polyurethane or the like in areas 13 and 14 and these are somewhat critically located to lie in specific areas of the loop. If desired the straight strap 10 may be first lightly impregnated throughout its entire length, ironed between presser members 12 as shown in FIG. 5 and then subjected to more intense impregnation in the areas 13 and 14 which are shaded in the drawings,

gated edge area of the straight woven strap while the body of the strap remains unheated.

3. A process of making a check strap as defined in claim 1, further characterized in that the woven strap is reinforced and smoothed by impregnating with polyurethane in areas adjacent to both ends of the straight strap.

4. A check strap constructed in accordance with the process of claim 1, secured in preformed conical loop formation at both ends at a fixed point and impregnated with polyurethane in an area reeved by the picker stick in moving to the end of its driving stroke.

5. A check strap constructed in accordance with the process of claim 1, having its ends overlapped and secured together at a fixed point in a loom thereby imparting a preformed conical looped formation to the strap, and friction fingers engaging the strap at the other

side of the loop, the strap being impregnated with polyurethane in that portion of the strap that is reeved about the picker stick in its driving stroke.
